US00D843559S

(12) **United States Design Patent** (10) **Patent No.:** **US D843,559 S**
Gibb et al. (45) **Date of Patent:** **** Mar. 19, 2019**

(54) **FUEL TANK FRAME**

(71) Applicant: **Worthington Industries, Inc.**,
Columbus, OH (US)

(72) Inventors: **Gary Gibb**, Stow, OH (US); **Michael Pintz**, Fairview Park, OH (US);
Stephen Polatas, North Canton, OH (US)

(73) Assignee: **WORTHINGTON INDUSTRIES, INC.**, Columbus, OH (US)

(**) Term: **15 Years**

(21) Appl. No.: **29/563,689**

(22) Filed: **May 6, 2016**

Related U.S. Application Data

(63) Continuation of application No. 29/520,243, filed on Mar. 12, 2015, now Pat. No. Des. 759,229, which is a continuation of application No. 29/473,251, filed on Nov. 20, 2013.

(57) **CLAIM**

The ornamental design for a fuel tank frame, as shown and described.

DESCRIPTION

FIG. 1 is a perspective view of a fuel tank frame; FIG. 2 is a back view of the fuel tank frame of FIG. 1; FIG. 3 is a front view of the fuel tank frame of FIG. 1; FIG. 4 is a first side view of the fuel tank frame of FIG. 1; FIG. 5 is a second side view of the fuel tank frame of FIG. 1, wherein the second side is opposite the first side of FIG. 4;

FIG. 6 is a top view of the fuel tank frame of FIG. 1; and, FIG. 7 is a bottom view of the fuel tank frame of FIG. 1.

(Continued)

The broken lines illustrate portions of the fuel tank frame and are also bounds of the claimed design, and form no part thereof.

1 Claim, 2 Drawing Sheets
